(57) **CLAIM**

The ornamental design for a submersible water toy, as shown and described.

DESCRIPTION

FIG. 1 is a perspective view of a submersible water toy; FIG. 2 is a top view of the submersible water toy illustrated in FIG. 1; FIG. 3 is a bottom view of the submersible water toy illustrated in FIG. 1; FIG. 4 is a left side view of the submersible water toy illustrated in FIG. 1; the right side view being a mirror image of the left side view; FIG. 5 is a front end view of the submersible water toy illustrated in FIG. 1; the rear end view being a mirror image of the front end view; and, FIG. 6 is a perspective view of the submersible water toy of FIG. 1, illustrating only the claimed portion of the design. The dot/dash lines which define the boundary of the claimed design do not form part of the claimed design. The broken lines are for environmental purposes only and form no part of the claimed design.

UNITED STATES PATENT AND TRADEMARK OFFICE
CERTIFICATE OF CORRECTION

PATENT NO. : D648,817 S
APPLICATION NO. : 29/296065
DATED : November 15, 2011
INVENTOR(S) : Jerry Fielding

Page 1 of 1

It is certified that error appears in the above-identified patent and that said Letters Patent is hereby corrected as shown below:

On the Title page, item (63) (Related U.S. Application Data), insert the following:

--Continuation of application No. 29/277,072, filed on February 13, 2007, now Pat. No. D576,244, which is a divisional of application No. 29/217,400, filed on November 16, 2004, now Pat. No. D536,760, and is a continuation of application No. 10/989,939, filed on November 16, 2004, now abandoned.--

On the Title page, in the Description prior to the figure descriptions, insert the following:

--This Design Patent Application is a continuation of U.S. Design Patent Application No. 29/277,072, entitled "Submersible Water Toy," filed February 13, 2007, now Pat. No. D576,244, which is a divisional of U.S. Design Patent No. D536,760 S, entitled "Submersible Water Toy," filed November 16, 2004; and a continuation of U.S. Patent Application No. 10/989,939, entitled "Submersible Water Toy and Related Methods of Use," filed November 16, 2004.--

Signed and Sealed this
Fifth Day of August, 2014

Michelle K. Lee
Deputy Director of the United States Patent and Trademark Office
